(57) **CLAIM**

The ornamental design for the case for reading glasses, as shown and described.

DESCRIPTION

FIG. 1 is an isometric view of a case for reading glasses in accordance with a preferred embodiment of my design; FIG. 2 is a front view of the case for reading glasses of FIG. 1;

FIG. 3 is a rear view of the case for reading glasses of FIG. 1; FIG. 4 is a top view of the case for reading glasses of FIG. 1; FIG. 5 is a bottom view of the case for reading glasses of FIG. 1;

FIG. 6 is a right side view of the case for reading glasses of FIG. 1; and,

FIG. 7 is a left side view of the case for reading glasses of FIG. 1.

The phantom lines and the dashed lines shown in the figures represent environmental subject matter and form no part of the claimed design.
